(57) **CLAIM**

The ornamental design for a pressure washer gun as shown and described.

DESCRIPTION

FIG. 1 is a perspective view of a pressure washer gun showing my new design;

FIG. 2 is a left view thereof;

FIG. 3 is a right view thereof;

FIG. 4 is a front view thereof;

FIG. 5 is a rear view thereof;

FIG. 6 is a top view thereof;

FIG. 7 is a bottom view thereof; and,

FIG. 8 is another perspective view thereof.

The broken lines illustrate portions of the pressure washer gun and form no part of the claimed design.

1 Claim, 8 Drawing Sheets
